UNITED STATES PATENT OFFICE.

PIERRE DANSEREAU, OF MONTREAL, CANADA.

ROLLER-BEARING.

SPECIFICATION forming part of Letters Patent No. 561,971, dated June 16, 1896.

Application filed February 17, 1896. Serial No. 579,624. (No model.)

To all whom it may concern:

Be it known that I, PIERRE DANSEREAU, a citizen of the Dominion of Canada, residing in the city and district of Montreal, in the Province of Quebec, Canada, have invented certain new and useful Improvements in Roller-Bearings; and I do hereby declare the following to be a full, clear, and exact description of the invention, such as will enable others skilled in the art to which it appertains to make and use the same.

My invention has reference to a roller-bearing especially adaptable to carriage-axles, but that can be used for bearings on line-shafting, &c.; and it consists in rollers inserted between the box onto which is placed the hub and a tempered bush placed directly over the journal of the axle, so that it is not subject to wear, and the tempered bushes and rollers are very easy and cheaply replaced. I provide rollers at both ends of the journal, this allowing the box surrounding it, and onto which is placed a wheel-hub of approved construction.

This invention relates to roller-bearings; and it consists in the novel construction and combination of the parts hereinafter fully described and claimed.

In the drawings, Figure 1 is a general outline elevation. Fig. 2 is a longitudinal section. Fig. 3 is a section on line X X of Fig. 2. Fig. 4 is a section on line Y Y of Fig. 2. Fig. 5 is an elevation of my rollers when kept in place by means of rings. Fig. 6 is a plan view of same.

A is an ordinary axle, over the journal B of which is placed the sleeve or box C, onto which is placed the hub of the wheel. (Not shown.) This sleeve or box C is enlarged at each end C' and C², so as to permit the insertion of my rollers, and its inside diameter in the intervening portion C³ is just enough to clear the journal B, so that the latter does not touch it.

D is an ordinary collar on the axle A, provided with the leather washer d; also, the lost motion at its outer end E can be taken up in any suitable well-known way, while my rollers consist in a series of rollers F, inserted in the portions C' and C² of the sleeve or box C over tempered bushes G, fitting loosely on the

journal B of the axle A, so as to be easily inserted and extracted and perfectly free to turn as they please.

The rollers F are held in place by abutting against the shoulders formed by the enlargement of the sleeve or box C and by means of the washers H and small annular projection J, over which is placed the washer K. The washers H and K can be made out of any suitable material, but preferably out of steel.

Instead of putting my rollers F in loosely I can secure them in two rings P, Figs. 5 and 6.

To remove the rollers, all that is necessary to do is to take off the wheel, remove the washers H and K, and pull out the bushes G, when if the rollers F are loose they will fall out, while if they are secured by end bearings in the rings P they are removed bodily. Of course to insert new ones the bushes G are first inserted, and then the rollers, and if the arrangement is as shown on Fig. 2 the annular projection or shoulder J is cut away for a short distance, (not shown on the drawings,) so as to permit the passage of a roller, so that they are pushed in through this opening.

Having described my invention, what I claim, and desire to secure by Letters Patent, is—

The combination, with an axle provided with a journal B having a collar D at one end, and a screw-threaded projection N at the other end; of a washer d of soft material next to the collar D; a sleeve encircling the journal and provided with cylindrical chambers at its ends, the outer chamber C' having an annular projection J; bushes G journaled on the bearing in the said chambers, rollers F interposed between the said bushes and the inner faces of the chambers, a washer H arranged between the rollers and the washer d at the inner end of the journal, a washer K bearing against the projection J, and a nut engaging with the projection N and bearing against the washer K, substantially as set forth. 95

In testimony whereof I affix my signature in presence of two witnesses.

PIERRE DANSEREAU.
